UNITED STATES PATENT OFFICE

GEORGE H. HAMILTON, OF GRAND RAPIDS, MICHIGAN, ASSIGNOR TO AMERICAN SEATING COMPANY, OF GRAND RAPIDS, MICHIGAN, A CORPORATION OF NEW JERSEY.

AISLE LIGHT.

Application filed April 7, 1927. Serial No. 181,680.

The present invention relates to lighting means, particularly such as are employed for lighting the aisles of theatres and the like; and its object is to provide means of 5 that character improved in certain respects hereinafter appearing; and more particularly to provide such means which may be readily mounted or demounted.

This and any other and more specific objects hereinafter appearing are attained by, 10 and the invention finds preferable embodiment in, the structure or device hereinafter particularly described in the body of this specification and illustrated by the accompanying drawings, in which:

Figure 1 is a view of the outer side of the upper portion of a seat or chair adjacent the aisle of a theatre, and provided with my lighting means;

Figure 2 is a vertical sectional view thereof taken on line 2—2 of Figure 1;

Figure 3 is a view in perspective of the casing containing the lamp; and

Figure 4 is a sectional view of a portion 25 of the casing taken on line 4—4 of Figure 2.

In the accompanying drawings, my lighting means is shown applied to the aisle-side of a theatre chair or seat. This seat has the upright end or supporting member 1 and 30 the back support 2. This support 1 has a chamber or socket 3 open at 4 to the inner side 5 of the support, and an opening, the light-emitting elongated slot 6, extending from the socket to the other (the outer) side 35 of the support.

An open rock-bearing is formed in this support adjacent its inner side 5 and the mouth 4 of the socket. A lamp, the electric light bulb 10, is carried inside a casing member 11 removably seated in said socket and having an outer wall 12 and an opposite wall portion 13 provided with spaced openings 14 which register with the light-emitting slot 6 so that the light from the lamp 10 may 45 shine through said openings 6 and 14 upon the floor of the aisle.

This casing has, adjacent its lower outer corner, a rib or rock journal 15 which may be inserted into the bearing 8, whereupon 50 the casing may be swung inwardly (turning on said bearing) to its seated position in the socket shown in Figure 2. The upper wall 16 of the casing, opposite the rib 15, is

springable so that, when the casing is swung to seated position, said wall is pressed downwardly until its projection 17 snaps into a keeper depression 18 in the support and 55 yieldingly holds the casing in its seated position.

A chisel or the like may be thrust between 60 the support and the upper wall 16 of the casing and its point engaged in the depression 19 of said wall to swing the casing outwardly in order to remove the same when desired.

The invention being intended to be pointed out in the claims, is not to be limited to or by details of construction of the particular embodiment thereof illustrated by the drawings or hereinbefore described.

I claim:

1. In a device of the character described; a support having a socket open to one side of the support, an open rock-bearing adjacent said side, and a light-emitting opening 75 from the socket to the other side of the support; a removable casing swingably movable to and from seated position in the socket and having an outer wall and an opposite wall provided with spaced openings 80 registering with the light-emitting opening, and a rock journal removably turning in the bearing in the seating and unseating movements of the casing, the casing oppositely to said journal springably engaging the support to yieldingly hold the casing in seated 85 position; a lamp carried in the casing.

2. In a device of the character described; a support having a socket open to one side of the support, an open rock-bearing adjacent 90 said side, and a light-emitting opening from the socket to the other side of the support; a removable casing swingably movable to and from seated position in the socket and having an outer wall and an opposite wall provided with spaced openings 95 registering with the light-emitting opening, and a rock journal removably turning in the bearing in the seating and unseating movements of the casing; a lamp carried in 100 the casing.

In testimony whereof I have hereunto set my hand at Grand Rapids, Michigan, this 4th day of April, 1927.

GEORGE H. HAMILTON.
